UNITED STATES PATENT OFFICE.

CHARLES C. STUTZ, OF PITTSBURGH, PENNSYLVANIA, ASSIGNOR TO SYNTHETIC HYDROCARBON COMPANY, OF PITTSBURGH, PENNSYLVANIA, A CORPORATION OF DELAWARE.

FURNACE FOR TREATING HYDROCARBONS.

1,359,931.

Specification of Letters Patent. Patented Nov. 23, 1920.

Application filed October 30, 1915, Serial No. 58,906. Renewed March 15, 1919. Serial No. 282,968.

To all whom it may concern:

Be it known that I, CHARLES C. STUTZ, residing at Pittsburgh, in the county of Allegheny and State of Pennsylvania, a citizen 5 of the United States, have invented or discovered certain new and useful Improvements in Furnaces for Treating Hydrocarbons, of which improvements the following is a specification.

10 In the practice of the Rittman process for treating hydrocarbons, as described in Bulletin No. 114 of the Bureau of Mines, it is desirable to maintain a high temperature at the upper end of the tube where the 15 oil is injected so as to effect a practically instantaneous vaporization of the material treated, a higher or decomposing temperature in the cracking zone, immediately below the portion where vaporization occurs,

20 and a lower temperature below the cracking zone. The object of the invention described herein is to provide for the regulation of the heat applied to the tube, so as to insure the proper heating of the different portions 25 of the tube in accordance with the reactions desired in the different zones. The invention is hereinafter more fully described and claimed.

In the accompanying drawings forming 30 a part of this specification, Figure 1 is a vertical section of my improved furnace, the plane of section being indicated by the line I—I, Fig. 2; Fig. 2 is a sectional plan view, the plane of section being indicated by the line II—II Fig. 1; Figs. 3 and 4 are sectional elevations of the lower portions of 35 the furnace, the planes of section being indicated by the lines III—III, IV—IV, respectively, in Fig. 1; and Fig. 5 is a sectional elevation on a plane indicated by the line V—V, Fig. 1. Fig. 6 is a sectional plan view, the plane of section being indicated by the line VI—VI, Fig. 1.

As clearly shown in Figs. 1, 2 and 5, the 40 tubes 1 into which the material is fed through the pipe 2, are arranged in a portion of the furnace intermediate the combustion chambers 3 and 4, the former which is designed to heat the upper portion of the 45 tubes being preferably made the larger in order to insure the required higher heating of such upper portions. As shown in Figs. 1 and 2, it is preferred to divide the lower portion of the larger chamber 3 into a series

of compartments by intersecting walls 5, so 55 that there may be an even flow of the products of combustion up through the checker-work, which is preferably arranged in the upper portion of the chamber. From the chamber 3, the products of combustion flow 60 through the passage 6 around the upper portions of the tubes 1 and down through the chamber 7 through which the tubes 1 pass. From these tube-containing chambers, the products of combustion escape 65 through the ports 8 into the passage 9, the lower end of which connects with a passage 10 leading to the stack 11. It is preferred to arrange a deflecting hood 12 over the portion of the combustion chamber farthest 70 from the tube containing chambers as shown in Fig. 1.

By reference to Figs. 1 and 5, the lower portions of the tubes 1 are inclosed in chambers 13, separated from the chambers 7 by 75 horizontal walls or partitions 14, located below the outlet ports 8 of the chambers 7. The chambers 13 have inlet ports 15 connecting with side passages 16, which in turn connect with opposite sides of the combustion chamber 4 as shown in Figs. 1, 4 and 5. As shown in Fig. 1, an auxiliary roof or top 80 17 closes the combustion chamber 4 which is also separated from the other portions of the furnace by a vertical wall 18. The lower 85 ends of the chambers 13 connect with flues 19 leading to a stack 20.

It will be observed that the combustion chamber 3 is made much larger than chamber 4, as the former is required to supply 90 sufficient heat to raise the upper portions of the tubes 1 to a cracking or decomposing temperature, while the latter serve merely as an auxiliary to prevent the lower portions 95 of the tubes becoming cooler than is desirable.

I claim herein as my invention:

1. In a furnace for treating hydrocarbons, the combination of a plurality of vertically arranged tubes, independent chambers inclosing the upper and lower portions of said tubes, a combustion chamber connected to the chambers inclosing the upper portions of the tubes and a combustion chamber isolated from the other combustion chamber, 105 and connected to the chambers inclosing the lower portions of the tubes.
2. In a furnace for treating hydrocarbons,

the combination of a plurality of vertically arranged tubes, a chamber inclosing portions of the tubes adjacent to the upper ends, a combustion chamber connected to the upper ends of said chambers, flues leading to a stack connected to the lower ends of said chambers, chambers inclosing portions of the tubes adjacent to the lower ends, a combustion chamber connected to the upper por-

tions of these lower heating chambers and 10 flues connected to the lower ends of the latter and to a stack.

In testimony whereof, I have hereunto set my hand.

CHARLES C. STUTZ.
